Patentverwertungs- & Elektro-Holding A.-G.,
Glarus, Switzerland, a corporation

Application March 21, 1944, Serial No. 527,500
In Switzerland May 23, 1941

13 Claims. (Cl. 250—27.5)

1

This invention relates to transmitting tubes and more particularly to tubes of the demountable type in which the tube enveloped is formed of a number of wall sections that are bolted or otherwise held in assembled relation. At least one of the joints between wall sections is sealed by plastic material and the envelope is exhausted, during operation of the tube, by a vacuum pump that runs either continuously or intermittently, depending upon the regulating system, to establish and maintain the required degree of vacuum within the tube.

In high-vacuum tubes electrons from the emitting cathode only reach the control grid when the potential of this grid is higher than that of the cathode. When these so-called primary electrons reach the grid, secondary electrons are released from the surface of the grid which generally travel on to the anode. A current will thus flow in the grid circuit which corresponds to the difference between the primary electron current ending at the grid and the secondary electron current commencing at the grid. This is based on the assumption, which is generally correct, that the discharge path is free from moving ions which would in their effect superimpose themselves on the aforementioned electron currents.

The number of secondary electrons which can be released by a primary electron depends only very slightly on the grid material and practically not at all on its temperature. The yield is, however, in the first place dependent on the grid voltage U_g , that is on the difference in potential between the grid and the cathode and also on the angle of impact of the primary electrons causing the secondary emission. Up to a voltage of 500 volts, with an impact perpendicular to the surface of the grid, the yield increases rapidly and then decreases slowly and continuously as the voltage exceeds this value. When the inclination of the electron path towards the vertical direction of impact increases, the yield of secondary electrons also increases, and the reversal in the rate of secondary emission occurs at a higher value of grid voltage. The secondary current thus varies with the grid voltage and it is also considerably influenced by the value of the anode voltage and the relative location of the electrodes. When the secondary electron current exceeds the primary electron current, the direction of the current in the grid circuit is reversed.

Such an irregular relationship between the grid current and grid voltage, which furthermore changes during service as experience has shown,

2

results in a large variation in the loading of the control stage connected to the grid. When transmitting tubes are used whose characteristic curves have negative portions, wild oscillations can easily occur which together with the varying load on the control stage may cause appreciable distortions in the transmission. Although with transmitters which are employed only for the generation of high frequency power, for instance for chemical or thermal purposes, a high distortion factor is of minor consideration, even in such cases a grid current which increases rapidly with the grid voltage may be a disadvantage because the control stage may under certain conditions not be in a position to supply the corresponding grid power. Sealed-off transmitting tubes according to their constructional form and power have characteristics which are different for each particular tube. Such tubes must therefore be carefully selected for the purpose for which they are intended and this requires that large stocks have to be maintained and each tube tried out until the most suitable one is found.

25 A great advantage would, however, be achieved if the course or shape of the grid current curve could subsequently be adjusted to suit the problem under consideration. By this means the replacement of such tubes would be greatly simplified and spare stocks could be kept considerably smaller. Tubes which have for instance to operate in push-pull connection could then also be adjusted as regards the grid currents so that distortion is still further reduced. Above all, however, the best possible grid current curve for each constructional form of tube, could be obtained independently of the various differences due to manufacture. In the ideal case for instance the grid current should only increase slightly with the grid voltage and then remain approximately constant at higher voltages.

Objects of this invention are to provide electron tubes having parts that are relatively movable, during operation of the tubes, to attain the advantage above stated. An object is to provide a demountable tube having cathode and control grid elements arranged and supported for angular adjustment to alter the grid current characteristic of the tube. More specifically, an object is to provide a demountable tube having a cathode in the form of parallel hot wires parallel to the tube axis, a control grid consisting of or including a plurality of rods parallel to the cathode wires, and supporting members for the cathode and grid electrodes that are angularly ad-

justable about the tube axis in such a manner that these electrodes can be rotated relatively to each other even when the tube is in operation.

These and other objects and advantages of the invention will be apparent from the following specification when taken with the accompanying drawings in which:

Figs. 1 and 2 are grid voltage-grid current curve sheets typical of two tubes that exhibit, respectively, an irregular and a regular relationship of current and voltage;

Figs. 3a and 3b are schematic cross-sections through the cathode and control grid electrodes of a tube embodying the invention, the views showing different angular relationships of the electrodes;

Figs. 4a and 4b are similar schematic cross-sections showing different relative locations of the electrodes in another embodiment of the invention;

Fig. 5 shows a constructional example of a demountable tube in longitudinal section, whilst Figs. 6-8 are cross-sectional views to an enlarged scale of this tube, along the lines of sections 6-6, 7-7 and 8-8 of Fig. 5, respectively.

In the Figs. 1 and 2 curve sheets, the abscissae represent the grid voltage U_g and the ordinates represent values of grid current and grid current components established during operation of two tubes of different electrode geometry. The resultant grid current J_g , which is the dominant value, can be measured and plotted against impressed values of grid voltage U_g . The grid current may be assumed to be the difference between the primary electron current J_p causing the secondary emission and the secondary electron current J_s . If the latter predominates, the resultant grid current J_g will become negative and there will be a sharp drop in the grid current-grid voltage characteristic curve, for example over the range of from 200 to 500 volts on the grid in the case illustrated by the Fig. 1 curve. When the primary electron current J_p is greater than the corresponding values of secondary electron current J_s over the entire grid voltage range, the resultant grid current J_g does not fall to negative values, see Fig. 2.

Electrode arrangements that result in different grid current characteristics are shown schematically, Figs. 3a to 4b, in cross-section through the cathode and control grid perpendicular to the tube axis. The wires of the cathode K and the rods G of the grid, which in this case is assumed to be a rod grid, can according to Figs. 3a and 3b be located in two symmetrical positions which are obtained by a relative rotation of 45°. Between these extreme positions a uniform variation of the relative positions of these electrodes is possible. The anode is to be considered as a coaxial cylinder which surrounds both electrodes. Tests have shown that the yield in the region of the aforementioned maximum of the secondary emission with the electrodes located as in Fig. 3a is so much greater than when positioned as in Fig. 3b, that in the former case the grid current will become negative as shown in Fig. 1 whilst when in the position shown in Fig. 3b it always remains positive (Fig. 2).

If the other conditions that affect tube operation remain unaltered, the electrode geometry, i. e., the spacing and the relative position of the electrodes, is therefore of great importance as regards the shape of the grid current and grid voltage characteristic. This is due to the field formation in the immediate vicinity of the grid

surface which in the case of Fig. 3b is greatly influenced by the space charge surrounding the cathode. In this case not only does the larger field strength prevent the secondary electrons emerging mainly towards the axis from leaving the vicinity of the grid but the impact of the primary electrons which is mainly perpendicular is in itself the cause of a smaller yield. In the position shown in Fig. 3a less primary electrons reach the control grid but under much more favourable conditions for releasing and transmitting secondary electrons to the anode.

In another embodiment of the invention, as shown schematically in Figs. 4a and 4b, the cathode wires are evenly distributed around the electrode circumference. It will be readily appreciated that in this case the effect of the rotation on the tube characteristic under consideration will be smaller, the maximum angle of rotation amounting to 15° in this particular case. According to the purpose for which the tube is intended to be used it may be an advantage for the cathode wires which are generally present in large numbers to be distributed evenly, or in groups as shown in Figs. 3a and 3b, whereby in the latter event it is preferable if the number of groups corresponds to the number of grid rods. Transmitter tubes, particularly for small powers, are often constructed with spiral grids. In such cases the supporting rods for the grids play the same part as the grid rods mentioned above. In order to increase their influence when they are rotated about the tube axis the ratio between the number of cathode wires and the number of grid rods should be made a whole number. On the other hand when rod grids are used, the sensitiveness of the displacement can often be increased when the ratio of the number of cathode wires to that of the grid rods is not a whole number.

It is found that the accuracy with which the grid current characteristic curves can be adjusted can be greatly increased if the number of cathode wires is greater than the number of parallel grid rods. Both in the case of an even or irregular distribution of the cathode wires around the periphery of the cylindrical array of cathode elements it is an advantage if these are arranged in groups, whereby the wires of any one group are subjected to a heating current of the same polarity. Between these wires and between these latter and the anode considerable forces prevail when the heating power and voltage is high. There is mutual repulsion between the wires of each group and therefore these must be connected together in a circumferential direction in at least one diametrical plane, the number of such planes depending upon the total length of the wires. In order to compensate the radial tensile pull of the anode these wires are also connected together by means of diametrical cross-wires, diametrically opposed cathode wires of the same polarity being connected together. In Fig. 4b such stiffening wires are indicated, T being the tangential and R the radial stiffeners. These latter are expediently connected together at the centre of the tube section, so that the structure is stiffened still further. The cross-wires indicated by broken lines have a different polarity to those shown in full and must therefore be located in different diametrical planes so as to prevent them from coming in contact with each other.

The manner in which the electrodes can be rotated while the tube is in service and under vacuum will be readily understood with reference to

Figs. 5-8. The demountable tube consists essentially of an anode A inside of which the cathode K and the grid G is located. The cathode K comprises two groups of parallel cathode wires K₁ and K₂ that are connected at their lower ends to a disk or ring k, the former group being fixed to the central rod E and the latter group K₂ to the concentric tubular elements F. Elements E and F are held in position by cathode supporting disks J and U which are insulated from each by a cathode insulator L. The lower cathode disk U rests upon the annular disk M, the disks being detachably united and sealed to each other by thermoplastic material N to constitute a demountable joint that may be opened, upon heating of the sealing material, for removal of the cathode assembly. The control grid G is a spiral wire grid wound on grid supporting rods O which are fixed to a grid disk P that is spaced from the disk M by the insulating cylinder L'. Between this latter flange P and the anode A is an anode insulator Q. Each group of cathode wires K₁, K₂ is provided with diametrical cross-wires or stiffeners R₁ (Fig. 7) and R₂ (Fig. 8) respectively by means of which diametrically opposed wires of the same polarity are connected together, each group of stiffeners being located in a different diametrical plane. Circumferential stiffeners T₁, T₂ can also be provided. The envelope or wall of the tube is constituted by a number of sections—namely, the disks J, N, U, M and P, the cylindrical insulators L, L' and Q, and the cylindrical anode A, the several adjacent wall sections being separable from and sealed to each other, as is conventional in demountable tubes. The lower end of the anode A is connected, through the insulating end of the anode A is connected, through the insulating cylinder L'', with the molecular vacuum pump S which establishes and maintains the desired degree of vacuum within the tube during operation thereof.

For adjustment of the operating characteristic of the tube by rotation of the cathode wires K₁, K₂ relatively to the grid or grid supporting rods O it is merely necessary to heat up the joint N between the disks M and U, say up to about 80° C., at which temperature it becomes plastic whereupon cathode disks U and J together with their respective cathode wires K₂ and K₁ can then be rotated relatively to the grid supports O. This rotational movement is thus achieved without breaking the tube joints or affecting the vacuum inside the tube.

The use of tubes according to the invention for push-pull connections is not only a great advantage as regards replacements but also as regards the possibility of rapidly compensating alterations in the performance of the tube, such as for instance when changes occur in the yield of the secondary emission due to vaporised cathode material reaching the grid.

This application is a continuation-in-part of, and is substituted for, our copending application Ser. No. 441,850, filed May 5, 1942, now abandoned.

We claim:

1. A demountable transmitting tube of the type comprising an envelope including a plurality of wall sections, a cathode and a control grid supported by wall sections insulated from each other, and a joint sealed by thermoplastic material between said supporting wall sections, characterized by the feature that the cathode consists of a plurality of parallel wires and the control grid consists of parallel rods, the cathode wires and

- grid rods being parallel to and both arranged around the common tube axis, said wall sections which support said cathode and said control grid respectively being relatively rotatable for angular adjustment of the cathode wires and control grid rods upon softening of the thermoplastic sealing material while the tube is under vacuum.
- 5 2. Tube as in claim 1, wherein said axially parallel wires forming the cathode are non-uniformly spaced about the tube axis but mounted in groups.
- 10 3. Tube as in claim 1 wherein said cathode wires are non-uniformly spaced circumferentially in a number of groups equal to the number of axial rods of the grid.
- 15 4. Tube as in claim 1, wherein the control grid comprises a spiral winding on said rods the ratio of the number of cathode wires to the number of supporting rods is a whole number.
- 20 5. Tube as in claim 1, wherein there is a whole number ratio between the number of cathode wires and grid rods, adjacent cathode wires of the same polarity being connected together in parallel in at least one diametrical plane in a circumferential direction and mutually stiffened by diametrical cross-connectors.
- 25 6. A demountable tube comprising a control grid electrode, cathode and anode electrodes, said cathode and grid electrodes each including a plurality of elements parallel to the axis of the demountable tube, a tube envelope including a plurality of wall elements of conductive and insulating material respectively, means supporting said cathode and grid electrodes upon conductive wall elements insulated from each other, and thermoplastic sealing material between said conductive wall elements which support said cathode and grid electrodes, respectively, the control grid elements and cathode elements being adjustable with respect to each other upon heating the joint to soften the sealing material.
- 30 7. A demountable tube as recited in claim 6, wherein said cathode electrode comprises a cylindrical assembly of parallel wires, said wires being non-uniformly spaced circumferentially in groups.
- 35 8. A demountable tube as recited in claim 6, wherein said cathode electrode comprises a cylindrical assembly of parallel wires, said wires being non-uniformly spaced circumferentially in groups, each group including a plurality of uniformly spaced wires.
- 40 9. A demountable tube as recited in claim 6, wherein said cathode electrode comprises a cylindrical assembly of parallel wires, said cathode wires being non-uniformly spaced circumferentially in groups, there being a group of cathode wires juxtaposed to each control grid rod.
- 45 10. A coaxial cathode-grid assembly for a vacuum tube, said assembly including a cathode comprising a cylindrical assembly of a plurality of parallel wires arranged in a plurality of groups of adjacent wires, there being an even number of more than three groups, a grid surrounding said cathode and including circumferentially spaced rods parallel to the cathode wires, the number of grid rods being equal to the number of groups of cathode wires, the cathode wires of each group being connected in parallel and the cathode wires of each group being connected in series with the cathode wires of another group.
- 50 11. A coaxial cathode-grid assembly as recited in claim 10, wherein circumferentially arranged
- 55 75

members connect the cathode wires of each group.

12. A coaxial cathode-grid assembly as recited in claim 10, wherein diametrically arranged groups of cathode wires are connected in parallel, and diametrically arranged members connect and strengthen the cathode wires of the diametrically located groups.

13. A coaxial cathode-grid assembly as recited in claim 10, wherein diametrically arranged groups of cathode wires are connected in parallel, diametrically arranged members connect and strengthen the cathode wires of the diametrically located groups, and means circumferentially connects the cathode wires of each group.
